M. L. HAWKS.
GARMENT SUPPORT OR THE LIKE.
FILED APR 12, 1919.

Inventor,
Moses L. Hawks,
Geo. L. Wheelock
Attorney.

UNITED STATES PATENT OFFICE.

MOSES L. HAWKS, OF NEW YORK, N. Y.

GARMENT SUPPORT OR THE LIKE.

Application filed April 12, 1919. Serial No. 289,687.

To all whom it may concern:

Be it known that I, MOSES L. HAWKS, a citizen of the United States, and resident of New York, in the county of New York and 5 State of New York, have invented certain new and useful Improvements in Garment Supports or the like, of which the following is a specification.

This invention relates to garment supporters, more particularly to men's suspenders and to garment supports, such as garters.

It is known that the elastic webbing which is usually employed in the construction of such supporters deteriorates due to the rotting or oxidation of the rubber. One of the 15 objects of the present invention is to overcome this effect by providing a substitute elastic element of spring metal, such for instance, as closed coils of helically wound 20 wire, preferably of some non-oxidizable metal, as for instance, German silver. Another object of the invention is to provide a garment supporter which furnishes the necessary support and tension, and which 25 adjusts itself automatically to the degree of tension caused by the supporting or supported parts and which can readily be otherwise, but positively, adjusted to take up unnecessary length or to shorten the same.

30 Other objects of the invention are to provide a simple, practical and efficient supporting means, as for garments, or other apparel parts which are subjected to tension when in use.

35 These being among the objects of the present invention, the same consists of certain features of construction and combinations of parts to be hereinafter described and then claimed with reference to the accompanying 40 drawings illustrating a desirable embodiment of the invention; that is, in connection with men's suspenders, and in which drawings:

Figure 1, is a front elevation of a portion 45 of a pair of men's suspenders showing the normal position of the parts, when not placed under tension, said figure being partly in section on the line I—I, Fig. 2.

Figure 2, is a side elevation of the same

parts partly in section on the line II—II, 50 Fig. 1; and

Figure 3, is a front elevation of the parts shown in Fig. 1; said parts being placed under tension.

In the drawings a suitable construction 55 for men's suspenders is illustrated although it is to be understood that the invention is applicable not only to suspenders, but to stocking supporters or other apparel parts. A flexible band or strap 10, of non-elastic 60 fabric, that is to say, fabric which contains no rubber, is provided to serve as a connecting medium between, for instance, the main suspenders 11, are adapted to support a guiding and binding member, preferably of flat sheet metal, and being provided with three apertures formed by parallel slots, 13, 14 and 15, which member furnishes a take-up device for adjusting the length between the suspenders 11, and the suspender ends. These 65 suspenders 11 have attached thereto an adjustable flexible attaching strap of non-elastic fabric webbing 16, and said strap is first passed by its free end through the slot 70 13 in the guiding-member 12, over a cross-bar 17, then through the intermediate slot 14, below which the free or tab end of the 75 said attaching strap 16, may depend. It will be noticed that by lacing the said flexible attaching strap through the guiding-member as described, a number of bights are produced in the same, thereby holding the 80 strap to the place to which it has been adjusted. The said attaching strap can readily 85 be adjusted by drawing out that portion of the strap between the slots 13 and 14 in the form of a loop, which will permit the strap to freely slide through the said slot.

Flexible band or strap 10, is passed 90 through the slot 15, in the guiding-member 12, so that one end of the same is on one side of the latter and the other end at the opposite side, said strap being guided in its movements by means of the cross-bar 18 95 at one side of the slot 15. In this way a loop or bight 19 is formed in the band or strap 10. To one end of the band or strap

10 there is secured a helical spring 20, to which end the intermediate portion 21, of the said spring is confined by a portion of the band or strap 10, which is passed around 5 it and stitched to the body of the said band or strap. The said spring 20 will then have projecting end portions which can be placed in parallel as shown at 22, and the extremities of the helical spring may be anchored in 10 any suitable manner to a metallic guide-loop or member 23. The preferred manner of attaching the said spring to the guide-loop 23, is to form eyes or hooks 24, on the extremities of said spring, and to engage the 15 same with the body of the metal guide loop 23. It is well known that such metallic guide-loops or members are usually formed of a single piece of wire bent into the form of a loop with the ends brought near together 20 facing each other, and this being so, it is a very simple matter to bend the end portions of the wire forming the loop so that the eyes or hooks 24, may be engaged therewith, after which the ends of the wire 25 of said loop may be bent back to their original position in alignment with each other. To the same cross-bar of the guide-loop 23 to which the metallic spring is attached the other and longer end portion of the looped 30 band or strap 10, may also be attached. It will be seen, therefore, that one end of the flexible band or strap 10, and the extremities of the metallic spring 20 are secured to the same cross-bar of the loop 23.

35 Over the other cross-bar of the loop 23, the suspender end 25, or other member, as of stocking supporters, is guided so as to have free movement, if such movement be desired, as would be so in the case of a suspender end. 40 It is preferred to guard and surround the major portion, at least, of the described tensioning construction, as by a sheath or flat tube 26, composed preferably of flexible material, such as leather or fabric, the opposite 45 walls of said sheath being secured together and to the flexible band or strap 10, as by a line of stitching 27. It will be observed that the said sheath extends as shown from a point adjacent the metal loop 23, to 50 a point adjacent the guiding and binding member 12, so that the parts within it will be sufficiently protected and prevented from contacting with the clothing.

55 It is to be noted that in the preferred construction of the described device there is but one elastic tension element, the same being preferably attached by the tension as the midlength thereof, so that a pull exerted by the band or strap 10, upon the intermediate 60 portion will pull more or less equally upon the parallel end portions of the spring, the flexible band or strap 10, sliding easily and freely over the cross-bar 18, of the guiding-member 12. It will also be observed

that there are but few parts, and that there 65 is not the least necessity to make use of elastic webbing.

It is obvious that the invention is susceptible of more or less modification so as to still be within the spirit and scope of the 70 claims.

What I claim as new and of my invention is,—

1. In a device of the class described, in combination, a looped flexible band, a guiding member for said band, a looped elastic member, firmly secured at the looped portion to one end of said band, and means for securing the other end of said band and the 75 ends of said elastic member. 80

2. In a device of the class described, in combination, a looped flexible band, a guiding member for said band, a looped helical spring, firmly secured at the looped portion by disposing some of its coils within a part 85 of said band, and means for securing another part of said band and the ends of said spring. 90

3. In a device of the class described, in combination, a looped flexible band, a guiding member for said band, a looped elastic member of spring wire, and consisting of two parallel portions composed of helically arranged convolutions and an intermediate portion at the loop-end, said intermediate portion being secured to a part of 95 said band, and means for securing another part of said band and the end coils of said elastic member. 99

4. In a device of the class described, in combination, a looped flexible band, a guiding member for said band, a looped elastic member secured at the looped portion to one end of said band, and consisting of spring 100 wire formed in helical convolutions, and a metallic loop, the other end of said band being secured to it as are also the end portions 105 of said elastic member. 100

5. In a device of the class described, in combination, a looped flexible band, a guiding member for said band, a helical tension spring secured to one part of said band, and loop or eye member, an end of said spring having an eye or hook which is hooked onto 110 said loop member, and said loop member and another part of said band secured together. 115

6. In a device of the class described, in combination, a looped flexible band, a guiding member for said band, a looped helical spring, firmly secured at the looped portion by disposing some of its coils within a part 120 of said band, means for securing another part of said band and the other ends of said spring, and a sheath for the operating parts of said spring. 120

7. In a device of the class described, in combination, a looped flexible band, a guiding member for said band, a looped, distensible, elastic member, of spring wire, and con- 125

sisting of parallel portions having eyes or hooks, and composed of helically arranged convolutions and an intermediate portion at the loop-end, said intermediate portion being secured to one end of said band, a metallic loop with which said eyes or hooks are engaged, means for securing another part 5 of said band and the said metallic loop, and

a sheath enclosing those portions of said structure in which said parallel spring portions are located, and, by which said spring portions are guided.

Signed at New York, in the county of New York, and State of New York, this tenth day of April A. D. 1919.

MOSES L. HAWKS.
